(Continued)*Primary Examiner* — Calvin E Vansant(74) *Attorney, Agent, or Firm* — Fishman Stewart PLLC(57) **CLAIM**

The ornamental design for a pin for a filter element, as shown and described.

DESCRIPTION

FIG. 1 is a top perspective view a pin for a filter element; FIG. 2 is a bottom perspective view of a pin for a filter element;

FIG. 3 is a front view of a pin for a filter element; FIG. 4 is a back view of a pin for a filter element; FIG. 5 is a top view of a pin for a filter element; FIG. 6 is a bottom view of a pin for a filter element; FIG. 7 is a left-side view of a pin for a filter element; and, FIG. 8 is a right-side view of a pin for a filter element. The broken lines depict portions of the pin for a filter element that form no part of the claim.
